SCAFFOLDING DEVICE

Stig Isakson, Portland, Oreg., assignor of one-half to George W. Schumacher, Portland, Oreg.

Application May 29, 1945, Serial No. 596,519

2 Claims. (Cl. 304—40)

1

This invention relates to scaffolding devices and the primary object of the invention is to provide braces for holding the ledgers and uprights of scaffolding in a fixed position relative to one another.

A further object of the invention is to provide a brace for bracing scaffolding that has bifurcated ends, said ends provided for embracing the ledgers and uprights and having a clamping means for holding the bifurcated ends of the brace securely to the uprights and ledgers being braced.

A still further object of my invention is to provide holding brackets for the ledgers of the scaffolding that are mounted upon a tubular body and said brackets having a clamping means associated therewith for gripping and holding the ledgers of the scaffolding to the tubular body, which in turn is mounted to the uprights of the scaffolding. A scaffolding device consisting of a tubular body having knife grips or brackets is covered in my pending application, Serial Number 585,138, but in this application I am illustrating the modified form of holding bracket.

These and other incidental objects will be apparent in the drawings, specification and claims.

Referring to the drawings:

Figure 1 is a fragmentary perspective elevation of my new and improved scaffolding device, including a bracing bar.

Figure 2 is a side view of my new and improved brace for scaffolding.

Figure 3 is an enlarged fragmentary detail of the clamping or gripping device used in connection with the brace.

Figure 4 is a fragmentary perspective view of another preferred form of supporting and gripping the cross ledgers of scaffolding to my new and improved scaffolding device.

Figure 5 is a fragmentary side view of the form shown in Figure 4, showing the ledger in section mounted therein.

In the drawings:

This invention consists of a brace 1, having bifurcated ends 2 and 3. The bifurcated end 2 consists of an offset jaw 4 forming part of the brace 1. On the inner face of the jaw 4 is a corrugated or roughened surface 5 for engaging the ledger 6 of the scaffolding as illustrated in Figure 1. The jaw 4 is secured to the brace 1 by the offset portion 7. The brace 1 extends beyond the offset portion 7 at 8, and has a wing bolt 9 threaded therethrough for engaging the opposite side of the ledger 6 and forcing the ledger

2

against the jaw 4 securely clamping the brace to the ledger.

The bifurcated end 3 consists of a jaw 10 secured to the brace 1, by the offset arm 11 forming part of the brace. The brace extends beyond the arm 11, and is indicated at 12. The inner side of the extension 12 is corrugated or roughened at 13 for engaging the upright 14 of the scaffolding. A wing bolt 15 is threaded through the jaw 10 and engages the upright 14, forcing the same against the roughened surface 13 of the extension 12 securely clamping the brace to the upright.

In operation the above described brace is quick to install, simple of construction and effective in its gripping quality and provides a very rigid brace in the construction of this type of scaffolding, for which I am applying for patent in another application, which consists of a tubular body 16 having holding brackets 17 for supporting the cross ledgers 6 and 18. I wish to include in this application the principle of providing outwardly extending points 19 from the body 16 against which is forced the cross ledgers 6 and 18 by the action of the wing bolts 20, which are threaded through the uprights 21 of the bracket 17. The wing bolts 20 may have points 22 formed thereon to engage the lumber and further hold the same from slipping or moving within the brackets 17.

I show a modified form of holding bracket in Figures 4 and 5 wherein a bracket arm, consisting of a flat bar 23 is fixedly secured to the body 16 at 24 by welding or other suitable means. A supporting brace or ledge is also secured to the body 16 and provides a resting place for the ledgers 26 indicated in broken lines. Extending outwardly from the ledge or support 25 is a bolt 27 which passes through a slot 28 within the flat bar 23. A winged nut 29 is threadably mounted to the bolt 27. Points 30 are provided on the inner side of the flat bar for engaging the ledger 26 when the ledger is put in place, resting upon the ledge 25. The flat bar is made to engage the side of the ledger by tightening up the wing nut 29, causing the points 30 to engage the lumber of the ledger, preventing the same from twisting when the wing nut is cinched up.

A modified form of brace is indicated in Figure 3, wherein a hooked end 31 is provided on the jaws 32 and is for the purpose of engaging the uprights, scaffolding and ledgers preventing the same from falling away and providing a more secure way of holding the brace in place, and at the same time providing a more rigid brace. In

the use of my new and improved bracing it can be readily mounted to the scaffolding and requires a minimum of space in the storage of the same.

I do not wish to be limited to the exact structure as illustrated, as other mechanical equivalents may be used for gripping the ledgers, still coming within the scope of my invention.

I claim:

1. A brace bar to unite and brace upright and ledger parts of scaffolding and comprising an elongated main bar of appropriate length, an integral offset near each end of the bar, providing with the bar a socket to receive the upright part of the scaffold at one end and the ledger part of the scaffold at the opposite end, the inner face of a part of each socket being roughened to engage the scaffold parts fitting that socket,

10

15

and means cooperating with a part of the socket to bear against the scaffold part therein and force the roughened face of the socket into the material of the scaffold part.

2. A brace bar to unite and brace upright and ledger parts of scaffolding and comprising an elongated main bar of appropriate length, an integral offset near each end of the bar, providing with the bar a socket to receive the upright part of the scaffold at one end and the ledger part of the scaffold at the opposite end, one wall of the socket at each end of the main bar being of greater length than the other wall of such socket, the wall of greater length being projected laterally to provide an end wall for the socket with the projected end wall having a terminal extended toward the shorter wall of the socket.

STIG ISAKSON.
